Inventor

C. C. Crowder,

By Clarence O'Brien, Attorney

UNITED STATES PATENT OFFICE.

CLARENCE C. CROWDER, OF BOST. TEXAS.

WRIST-PIN BEARING.

Application filed May 20, 1927. Serial No. 192,994.

The present invention relates to a wrist pin bearing and has for its principal object to provide a structure which may be easily and readily incorporated in the pitman.

5 A still further important object of the invention lies in the provision of a device of this nature which is simple in its construction, inexpensive to manufacture, strong and durable, efficient and reliable in use, and 10 otherwise well adapted to the purpose for which it is designed.

With the above and numerous other objects in view as will appear as the description proceeds, the invention resides in certain 15 novel features of construction, and in the combination and arrangement of parts as will be hereinafter more fully described and claimed.

In the drawing:

20 Figure 1 is an elevation showing a pitman with my improved wrist pin bearing mounted therein,

Figure 2 is a side elevation of the wrist pin bearing,

25 Figure 3 is a sectional view therethrough, and,

Figure 4 is a top plan view thereof.

Referring to the drawing in detail it will be seen that the numeral 5 denotes a pitman 30 having the usual opening therein to receive the wrist pin bearing. The numeral 6 denotes the lower segment of the bearing which is provided with depending ears 7 at its ends which may be bolted as at 8 or otherwise

35 secured to the sides of the pitman 5. This segment 6 is formed with a semi-cylindrical recess 9 which receives a semi-cylindrical bushing 10. Flanges 11 rise from the side edges of the segment 6 a distance from the recess 9 as is clearly illustrated in Figure 3. The numeral 12 denotes the upper segment

which has a semi-cylindrical recess 13 for receiving a semi-cylindrical bushing 14 to complete the bore of the bearing for receiving 40 the wrist pin. Projections 15 depend from the segment 12 one on each side of the recess 13 to be received between the flanges 11. A rib 17 extends across the top of the segment 12 and has an opening for receiving

45 the parallelopiped portion 18 which extends transversely thereof and terminates in rounded threaded extensions 19. The center portion of the parallelopiped portion 18 is provided with a lug 20 rising therefrom.

50 A cap 21 fits over the rib 17 and has notches 55

18' to receive the parallelopiped portion 18. This cap 21 is held in place by bolts 22 or in any other suitable manner. The rib and the segment 12 are provided with an orifice 23 for receiving a grease cup or the like as is 60 shown at 24 so that the wrist pin in the bushing structure 10, 14 may be lubricated. The structure 18, 19, has its portion 17 projecting beyond the edges of the pitman 5 in order that links 26 may be engaged thereon. Turnbuckles 27 are engaged with links 26 and links 28 are engaged with the turnbuckles and with a strap structure 29 fixed to the bottom of the pitman. Thus by turning these turnbuckles which have an opposite threaded engagement with the links 26 and 28 respectively, the straps may be tightened and the wrist pin bearing held firmly in place.

It is thought that the construction, operation, utility, and advantages of this invention will now be quite apparent to those skilled in this art without a more detailed description thereof. It will be seen that the upper segment 12 of the bearing structure 75 70 may be removed without disturbing the lower portion thereof and the bushings may be renewed if necessary. Thus the device is capable of easy installation and replacement.

The present embodiment of the invention 80 85 has been disclosed in detail merely by way of example since in actual practice it attains the features of advantage enumerated as desirable in the statement of the invention and the above description. It will be apparent 90 that changes in the details of construction, and in the combination and arrangement of parts may be resorted to without departing from the spirit or scope of the invention as hereinafter claimed or sacrificing any of 95 its advantages.

Having thus described my invention, what I claim as new is:—

1. A wrist pin bearing structure of the class described comprising a lower segment 100 having a recess in its upper portion for receiving a bushing segment, flanges rising from the upper face of the lower segment, one on each side of the recess, an upper segment having a recess in its lower face to 105 receive a bushing segment, flanges projecting downwardly from the lower face of the upper segment one on each side of its recess and adapted to be received between the flanges on the other segment, said upper 110

segment being provided with a rib on its upper face extending longitudinally with the recess therein and formed with a central opening, a bolt-like structure receivable in the central opening and having a center parallelopipede structure having rounded ended extensions, and means for holding said bolt-like structure in place.

2. A wrist pin bearing structure of the 10 class described comprising a lower segment having a recess in its upper portion for receiving a bushing segment, flanges rising from the upper face of the lower segment, one on each side of the recess, an upper segment having a recess in its lower face to receive a bushing segment, flanges projecting downwardly from the lower face of the upper segment one on each side of its recess and adapted to be received between the 20 flanges on the other segment, said upper segment being provided with a rib on its upper face extending longitudinally with the recess therein and formed with a central opening, a bolt-like structure receivable in the central opening and having a center parallelopipede structure having rounded end extensions, and means for holding said bolt-like structure in place, said means comprising a cap and fastening element for

holding said cap in place over the rib and 30 over the bolt-like structure.

3. A wrist pin bearing structure of the class described comprising a lower segment having a recess in its upper portion for receiving a bushing segment, flanges rising 35 from the upper face of the lower segment, one on each side of the recess, an upper segment having a recess in its lower face to receive a bushing segment, flanges projecting downwardly from the lower face of the 40 upper segment one on each side of its recess and adapted to be received between the flanges on the other segment, said upper segment being provided with a rib on its upper face extending longitudinally with the recess 45 therein and formed with a central opening, a bolt-like structure receivable in the central opening and having a center parallelopipede structure having rounded end extensions, and means for holding said bolt-like structure in place, said means comprising a cap and fastening element for holding said cap in place over the rib and over the bolt-like structure, the lower bearing segment being 50 provided with depending ears. 55

In testimony whereof I affix my signature.

CLARENCE C. CROWDER.
